UNITED STATES PATENT OFFICE.

JOHN F. KIRGAN, OF EASTON, PENNSYLVANIA, ASSIGNOR TO INGERSOLL-RAND COMPANY, OF JERSEY CITY, NEW JERSEY, A CORPORATION OF NEW JERSEY.

SURFACE CONDENSER.

Application filed November 2, 1927. Serial No. 230,554.

This invention relates to steam condensing apparatus and more particularly to surface condensers.

It is an object of this invention to enable the steam to be distributed to all parts of the condenser for the purpose of producing equal depth of steam penetration throughout the various parts of the condenser and for distributing steam to the various parts of the condenser in proportion to the thermal or steam condensing capacity of the cooling tubes. More specifically it is an object of the invention to enable equal or any desired depth of penetration to be obtained in that type of condenser in which the air devaporation is provided for by an internal air cooler and devaporizer.

Other objects and advantages of the invention will be in part obvious and in part pointed out hereinafter.

In the drawing forming part of the specification and in which similar reference characters refer to similar parts,

Figure 1 is a longitudinal vertical section through a condenser constructed in accordance with the practice of the invention, this section being taken along the line 1-1 of Figure 2, and looking in the direction of the arrows, and

Figure 2 is a cross section of the condenser taken along the line 2-2 of Figure 1 looking in the direction of the arrows.

Referring to the drawing, the condenser in this instance comprises a shell or casing A having a steam inlet B and outlets C and D for condensate remote from the steam inlet B. Within the shell A are arranged a plurality of steam condensing tubes E arranged transverse to the direction of steam flow, the tubes E being sealed at their ends in suitable tube sheets F at either end of the casing A. Cooling water is fed to the tubes E from an inlet water box G associated with one of the tube sheets F and such cooling water is removed at a discharge water box H at the opposite end of the shell and associated with the other tube sheet F.

This condenser is preferably of the single pass type in which the water flows through the tubes E in a single direction and is not returned to the tubes before having been cooled.

In such condensers it is evident that those sections nearer the inlet water box have greater steam condensing capacity than those

nearer the discharge water box, it being obvious that the warmer the water in the cooling tubes the less the steam condensing capacity. The tendency in the usual condenser is for the steam to penetrate less deeply in the cooler sections than in the warmer sections, since in the former the steam is condensed more quickly, due to the cooler tube surface. This condition tends to produce areas at the cooler end of the condenser, which are not utilized for condensing steam, since the steam normally will not reach to these areas before condensation. This invention has the advantage of providing means for drawing the steam to equal depths of penetration throughout the length of the condenser so as to utilize all of the cooling surface. To this end the condenser is divided into a plurality of compartments by transverse partitions J, in this instance three in number, thereby dividing the condenser into four compartments substantially sealed from each other near the bottom of the condenser so as to prevent leakage from one compartment to the other in regions adjacent the condensate outlets C and D which in this instance is the region at which air and uncondensables are removed from the main condensing compartments. The condenser in this embodiment of the invention is provided with an air cooling and devaporizing section within the shell A having walls K which converge upwardly. The walls K preferably form a wide opening at the lowest row of tubes E adjacent the entrance which here is adjacent to the condensate outlet also and the space between the walls is provided with cooling tubes L for devaporizing the air passing therethrough. The devaporizing section extends the length of the condenser and is also divided into compartments by partitions O which may be formed integrally, if desired, with the partitions J. The compartments thus formed are preferably sealed from each other and communicate with the corresponding compartments of the main condenser formed by the partitions J which seal the said main condenser compartments from each other in the regions adjacent the entrances to the devaporizing compartments of the devaporizing section. In this instance the entrances to the devaporizing compartments are at the space below the last rows of tubes E and L. At the apex of 110

each devaporizing section compartment is provided an air outlet P connected by means of a pipe Q leading preferably through the side of the casing A to suitable evacuating apparatus such has the steam jets R.

As shown in this instance, there are two condensate outlets C and D, each serving two compartments. The two cooler compartments are connected by a hydrostatic trap S and the two warmer compartments are similarly provided with a trap T. Thus the condensate formed in the coolest compartment may flow into the next coolest compartment through the trap S from which it is withdrawn at the condensate outlet C. Likewise the condensate formed in the warmest compartment is transferred to the next warmest compartment through the trap T and thence withdrawn by a suitable pump (not shown) from the condensate outlet D.

In the operation of the condenser the vacuums produced by the evacuating apparatus differ at each compartment. At the coolest compartment the vacuum drawn is the greatest in order to pull the steam to the lowest bank of tubes E. In the next cooler compartment this depth of penetration may be produced by less vacuum at the corresponding steam jet R and so on to the last compartment within which still less vacuum is provided for drawing the steam to the last row of tubes E.

Thus by the above construction are accomplished, among others, the objects hereinbefore referred to.

I claim:

1. A steam condenser comprising a shell having an inlet for steam and an outlet for condensate, a plurality of steam condensing tubes transverse to the direction of steam flow, a partition in said condenser dividing the casing into a plurality of compartments of different steam condensing capacity, a devaporizing section for air and uncondensable gases communicating with said compartments, said devaporizing sec-

tion being arranged within said condenser and having an upwardly extending apex and divided into compartments corresponding to the compartments of the casing, and means for producing different vacuums in the different compartments of the devaporizing section.

2. A steam condenser comprising a casing having a steam inlet and a condensate outlet, cooling tubes arranged transversely with respect to the path of the steam flow within the casing, a plurality of partitions transverse to the cooling tubes to form compartments substantially sealed from each other near the condensate outlet, an air and uncondensable gas devaporizing section within said condenser having walls converging upwardly, air outlets at the apex of said devaporizing section, said devaporizing section being divided into compartments by said partitions, corresponding to the compartments of said casing, and separate evacuating means associated with the air outlets of said compartments of the devaporizing section.

3. A steam condenser comprising a shell having an inlet for steam and an outlet for condensate, a plurality of steam condensing tubes transverse to the direction of steam flow, a condensing section a devaporizing section for air and uncondensable gases within the shell and having an air outlet, a partition within the shell dividing the condensing section into main condensing compartments and dividing the devaporizing section into devaporizing compartments corresponding to the main condensing compartments, said partition sealing the main condensing compartments from each other at the region of the entrances to the devaporizing compartments, and means for producing different vacuums in the various devaporizing compartments.

In testimony whereof I have signed this specification.

JOHN F. KIRGAN.
